UNITED STATES PATENT OFFICE.

JOHN E. HOWARD, OF ERIN, NEW YORK.

PLATFORM-BRIDGE.

1,131,783.

Specification of Letters Patent. Patented Mar. 16, 1915.

Application filed August 7, 1914. Serial No. 855,614.

To all whom it may concern:

Be it known that I, JOHN E. HOWARD, a citizen of the United States, residing at Erin, in the county of Chemung and State of New York, has invented certain new and useful Improvements in Platform-Bridges, of which the following is a specification.

This invention relates to certain new and useful improvements in platform bridges, which constructions are commonly called race-pieces by railroad employees when the same are employed in connection with railroading.

The primary object of this invention is to provide a removable bridge positionable between the platforms of adjacently positioned railway cars for the transfer of freight therebetween, and so constructed as to prevent any displacement of the bridge when in use, and thus preventing the accidental falling of both goods and employees.

A further object is to provide a bridge for employment with freight and transfer platforms so constructed as to prevent the same from accidental displacement, and being capable of fitting and forming a connection between platforms of variable height, as well as distances apart.

A still further object is to provide a race-piece or bridge adaptable for use for all equipment of the railroad, and engageable therebetween by means of an adjustable locking cleat slidably mounted thereon.

With these general objects in view and others that will appear as the nature of the invention is better understood, the same consists in the novel combination and arrangement of parts to be hereinafter more fully described, and illustrated in the accompanying drawings, and pointed out in the appended claims.

In the drawings forming a part of this application and in which like-designating characters refer to corresponding parts throughout the several views, Figure 1 is a perspective view of the device operatively positioned between two open freight cars. Fig. 2 is a perspective view of the under side of the device. Fig. 3 is a transverse sectional view thereof, and Fig. 4 is a detail enlarged view of one of the cleat connections.

Referring more in detail to the drawings, the invention broadly consists in a movable platform or bridge 10 which is adapted to be positioned between two freight cars such

as 11 for the purpose of readily transferring freight from one car to the other, it being of course understood that the bridge is equally adaptable for positioning between one car and a stationary platform, or between platforms and movable trucks.

The bridge is in the form of a flat board 10 having its opposite ends 12 beveled and is provided with a transverse cleat 13 rigidly secured to the bottom thereof and slightly spaced from one end of the board and in parallel relation to the said end. A movable cleat 14 of substantially the same thickness as the cleat 13, is slidably positioned beneath the board and adjacent the opposite end thereof from said cleat 13, and is positioned at all times parallel to said cleat 13 as well as to the adjacent end of the board.

The board is provided with arcuate slots 15 with enlarged upper portions forming a marginal shoulder 16 for each of said slots. A post 16' is positioned upwardly projecting from the cleat 14 adjacent the opposite ends thereof and projects through the adjacent slot 15 being provided with an enlarged head 17 adapted to ride upon the shoulder 16. An operating lever 18 is pivoted as at 19 to the lower face of the board and has a projecting handle 20 projecting outwardly from one side thereof. A rack 21 is secured to the lower face of the board, and projects over the lever 18 and is provided with a plurality of notches 22 on its under face and adapted to receive the lever when positioned in its desired adjustment, it being noted that the outer free end of the lever is normally maintained in engagement with the rack teeth.

A suitable connecting bracket 23 is rigidly secured to the inner face of the cleat 14 and is pivoted as at 24 to the lever 18 substantially centrally thereof. When it is desired to position the bridge between two platforms or cars, the cleat 14 is moved to its innermost point by moving the lever handle 20 as far as possible toward that end of the board upon which the cleat 13 is mounted. The board is then positioned with its ends resting upon the two platforms and with the cleat 13 flatly engaging the same, and whereupon a reverse movement of the lever handle 20 will force the cleat 14 against the other platform, thus firmly positioning the bridge and preventing any accidental displacement thereof, it being noted

that the lever 18 is then positioned in engagement with the teeth of the rack 21 for retaining the cleat 14 in its adjusted position. By this arrangement of elements, the bridge is so positionable between platforms of slightly different heights, as well as those positioned different distances apart.

While the forms of the invention herein shown and described are what are believed 10 to be preferable embodiments thereof, it will be understood that certain changes may be made therein without departing from the spirit of the invention as set forth in the claims.

15. What I claim is:

1. A platform bridge comprising a board having longitudinally positioned arcuate slots positioned therethrough and adjacent one end thereof, a fixed cleat secured beneath 20 the board and adjacent one end thereof, a movable cleat transversely positioned adjacent the opposite end of said board, posts carried by said movable cleat and extending through said slots, an adjustable operating 25 lever for said movable cleat.
2. A platform bridge comprising a spanning board having arcuate slots there-through adjacent one end thereof, a movable cleat beneath said board, posts carried 30 by said cleat and extending through said slots, and provided with heads countersunk

in the upper sides of said slots and movable therein, a transversely positioned operating lever pivoted at one end to said board, connecting means rigidly secured at one end to 35 said cleat and pivoted at its other end to said lever, and automatic locking means for retaining said lever in adjusted position.

3. A platform bridge comprising a spanning board, a spaced cleat secured beneath 40 one end of said board, a rack engaging said cleat and secured beneath the adjacent edge of said board, the said board being provided with arcuate slots at the opposite end thereof, and having countersunk encircling 45 shoulders, posts slidably mounted within said slots, and having heads positioned upon said shoulders, a removable cleat attached to said posts beneath said board, a resilient operating lever pivoted beneath said board, 50 and extending beneath said rack and adapted for automatically engaging the teeth thereof in its adjusted positions, connecting means pivoted to said lever and rigidly secured to said movable cleat.

55 In testimony whereof I affix my signature in presence of two witnesses.

JOHN E. HOWARD.
